UNITED STATES PATENT OFFICE.

CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS.

ELECTRIC-SWITCH-OPERATING MECHANISM.

Original application filed December 13, 1922, Serial No. 606,678. Divided and this application filed March 19, 1926. Serial No. 96,057.

This invention relates to electric switches and has particular reference to manually and electrically controlled switch-operating mechanism; and this application is a division of my co-pending application Serial No. 606,678, filed December 13, 1922.

An object of this invention is to provide an electric switch with operating mechanism including means to lock the switch in closed position and tripping means so arranged as to be controlled by any one or all of a plurality of tripping coils.

A further object of the invention is to provide switch operating mechanism arranged for both electrically controlled, automatic operation and manually controlled operation with manually controlled means to effect the opening of the switch at automatic speed, whereby to prevent the switch from being opened slowly.

The mechanism with which this invention is particularly concerned is adapted to be mounted on a switch board or panel. The tripping coils are adapted to be contained in a box or casing which is adapted to form a part of the supporting structure of the switch operating mechanism and may have various members of the switch operating members mounted directly thereon. Consequently whenever a coil burns out or for any reason it is desirable to remove or insert a coil, it is necessary to dismantle more or less of the operating mechanism before the coil box can be removed and access can be gained to the coils.

A particular object of this invention is to provide a construction for the actuating coils of an electric switch and the coil box enclosing them so that the coils can be readily removed from the box without disturbing the box or its associated switch operating mechanism.

A further object is generally to improve the construction of electrically-actuated operating mechanisms.

Fig. 1 is a side elevation of a face plate for an electric switch bearing the switch operating mechanism embodying the invention.

Fig. 2 is a plan view in section taken along lines 2—2 of Fig. 1.

Fig. 3 is a vertical sectional detail through

the coil box of the switch operating mechanism.

Fig. 4 is a view of the coil box as shown in Fig. 3 with certain parts removed to illustrate the method of removing the coils from the coil box.

As here shown, the switch operating mechanism embodying the invention includes a face plate 10 which is adapted to be mounted upon some suitable vertical support 11 by suitable means as the bolts 12. Said bolts may extend through said support 11 and secure to said support a suitable bracket 13 to which a bell crank lever 14 may be pivoted. Said bell crank lever may be actuated by the switch operating mechanism to move a rod 15 which may be connected in a suitable manner to an electric switch, not shown, which may be remotely disposed with respect to said face plate. A pair of links 17 may be secured in spaced relation to opposite sides of said bell crank lever 14 and extend through apertures in said support 11 and face plate 12 and be pivotally connected with a switch-operating lever 18. The lower portion of said face plate 10 is formed to provide an enclosure or tripping-coil box 19 and the front wall of said coil box may be formed or provided with projections 20; and the lower end of said lever 18 may be pivotally supported on a pin 21 which is or may be passed through said projections 20. Said lever 18 is adapted to be moved about its pivotal support to effect the opening and closing of the switch.

An operating handle 22 is provided by which the switch may be closed manually and, in accordance with this invention, means are provided which are so arranged that said operating-handle can not be manipulated to open the switch manually. Said operating handle may include the spaced bars 23 which are pivotally mounted on the pin 21 on opposite sides of said lever 18. Means are or may be provided by which said lever 18 and consequently the switch operating mechanism may be connected releasably with said handle. Said means includes the bracket 25 which is or may be secured to and between said bars 23 of the handle. A tripping latch 24 is pivoted on a pin 25 carried by said bracket. Said

lever 18 is or may be provided with a cam roller 26 rotatably supported at the upper portion thereof and said latch 24 is adapted to engage said cam roller releasably. Said operating handle is adapted to be locked releasably in switch-closed position and said latch 24 is adapted to be actuated both manually and electrically. Said lever 18 and the links 17 connected therewith are adapted to 10 be moved outwardly between the bars 23 of said handle by the weight of the switch mechanism, or pressure of the switch-opening springs, to switch open position. Said operating handle is adapted to be subsequently unlocked and moved towards the 15 left, Fig. 1, to effect the re-engagement of said latch 24 with the lever 18 whereby to permit the switch to be closed manually.

The operating handle locking means may 20 include the latch 30 which may be disposed in a slot in the arms 31 which are or may be extended outwardly from the face plate 19; and said latch is or may be pivoted on a pin 32 carried by said arms. Said latch is 25 adapted to engage a projection, as the cam roller 35, of said operating handle and hold said handle in substantially vertical or switch-closed position as shown in Fig. 1, and when moved upward, to release said 30 handle and permit it to be moved outwardly by its own weight, or manually to effect the re-engagement of said handle with the lever 18 with the switch operating mechanism. Said handle-locking latch 30 may be restricted in its movement by a pin 34 which 35 extends between the arms 31 of said face plate and through an enlarged hole 36 in said latch. Said latch may be normally spring pressed into handle holding position 40 by the coil spring 37 and said spring may be disposed in the slot between said arms 31 and be supported on a pin 38 connecting said arms. Said spring may bear against the bottom wall of said slot and the upper 45 portion of said latch above the pivot pin 32 thereof.

The operating mechanism is so arranged that the switch can not be opened by the handle but must be tripped open whereby to 50 release the switch mechanism from the handle and the mechanism is so arranged that the act of tripping the switch member also serves to release the handle-locking latch 30 from holding engagement with the operating 55 handle. For this purpose, said latch 24 is or may be provided with suitable manually-engageable means as the pin 40 which is or may be extended laterally on opposite sides of said latch and is adapted to be engaged 60 by the hand whereby to raise that portion of the latch and cause it to release the lever 18 of the switch operating mechanism whereby to permit the switch to open.

Said latch 24 is arranged to be moved 65 upwardly in the manual switch-opening

movement and engage a projection 41 of the handle locking latch 30 and thereby raise said latch and consequently unlock the handle; and said latches are or may be so arranged that the manual unlocking operation 70 also serves to move the handle outward, whereby but one hand only need be required to open and close the switch.

It is thus seen that the handle can not be conveniently unlocked until the switch has 75 been tripped and the tripping of the switch by the manual raising of the latch causes the switch to open at the same speed that it opens when automatically tripped. This result is highly advantageous in that it prevents a slow opening of the switch and consequently reduces the probability of burning the switch contacts and otherwise causing damage.

The electric switch tripping mechanism 80 may comprise a plurality of tripping coils; and the mechanism is so arranged that each trip coil by itself may be effective to trip the switch.

As here shown, the coil box 19 of the face 90 plate is of more or less triangular cross section and is adapted to contain three trip coils 45, each of which may be contained in a phase of a three phase circuit and act to trip the switch upon overloads in their respective phases or one or more of said coils 95 may be otherwise arranged to control the switch under different circumstances.

Said coil box 19 is or may be so arranged that the coils may be removed and replaced 100 without removing the face plate from its support or otherwise altering the arrangement of the mechanism.

For this purpose, the bottom wall 46 of said face plate is provided with an aperture 47 therethrough which is disposed preferably at the apex portion of the coil box; and said aperture is adapted to be at least as great in diameter as said coils 45 whereby to permit entrance of said coils to and 110 their removal from said coil box. Said aperture 47 is normally closed by a plate 48 which is adapted to enter said aperture and be substantially flush with the inner 115 face of the wall 46; and screws 49, or other suitable attaching means, may extend through the flange 50 of said plate whereby to secure said plate to the coil box.

Said trip coils 45 may include the center tubes 51 upon which the coils are formed 120 and the tubes 52 which are adapted to be loosely received within said tubes 51; and the movable core 52^a of the coils are or may be received in said tubes 52.

Said tubes 52 are or may be provided with 125 reduced and threaded upper portions 53 which are adapted to extend into and through openings 54 in the top wall 55 of said coil box. Internal screw threaded standards 56 may be threaded on said tubes 130

52 whereby to secure them removably in position. The lower wall 46 of said coil box and the plate 48 is formed with openings which are aligned with the openings 54 of the top wall of the coil box and said tubes 52 are adapted to be received removably therein.

The arrangement is or may be such that when said tubes 52 are secured in position 10 in the coil box with said coils 45 disposed thereabout, said coils are held securely in position against displacement. Said coils may be removed from the coil box by removing said tubes 52 therefrom and removing 15 the cover plates 48, whereupon the coils may be extracted from the coil box through the aperture 47 in the lower wall thereof.

The switch tripping means may include a tripping plate 60 of more or less triangular 20 form and each apex of said plate is or may be disposed in operative relation with a tripping coil contained in said coil box. Said plate may be formed with the triangularly disposed slots 61 therein which are located 25 in the apices thereof and the grooved heads 62 of pins 63 may be loosely received in said slots. Said pins 63 are or may be slidably supported in the standards 56 and are adapted to extend through said standards 30 into the interior of the tubes 52 of the tripping coils and be engaged by the cores 52^a of said tripping coils and raised vertically whereby to raise said tripping plate 60, and trip the switch. Said pins 63 constitute 35 tripodal supporting means for said plate and the arrangement of said plate 60 and pins 63 is or may be such that said plate is loosely, yet securely, supported on said pins and may fulcrum about any two thereof, 40 when one or more pins are raised. Said plate 60 is disposed beneath and in operative relation with the latch 24 and is adapted to engage and raise the inner end of said latch when one or more of said coils 45 is 45 effectively energized whereby to effect the tripping of the switch. Preferably, said tripping plate 60 is provided with a spring plate 65. Said spring plate is adapted to engage the latch 24 and may be raised to 50 varying positions above the plate 60 by suitable means, as by the adjusting screw 66, whereby to admit of slight variations of dimensions in the manufacture of the mechanism. Said plate 60 is or may be provided 55 with the apertures 60^a, which may be screw-threaded, by which auxiliary apparatus as, for instance, an under voltage release attachment, not shown, may be arranged to control the tripping of the switch, in addition to the tripping coils herein illustrated.

Said latch 24 is or may be bifurcated as by being provided with the spaced extensions 24^a secured to and disposed on opposite sides of the body of said latch. Said 60 latch-extensions are or may be so arranged

that the latch may be in effective position to be actuated by the tripping plate when the operating handle and lever 18 are being moved towards switch-closed position so that the switch may be tripped free from 70 the handle and be restored to open position if an overload is present on the circuit controlled by the switch when the contacts thereof are brought into engagement.

The construction may be otherwise modified without departing from the spirit of 75 the invention.

I claim:

1. Electrically actuated operating mechanism including a coil box having an aperture in one of its walls through which a coil is adapted to be passed, a tripping coil contained loosely in said box, externally-extended means arranged to secure said coil removably in place in said box, and a removable cover for said aperture, which cover normally comprises a support for said coil. 80

2. Electric switch operating mechanism including a support, a coil box mounted on said support, a tripping coil having a longitudinally axial passage removably contained within said box, and means extending through said passage and without said box to secure said coil removably in place. 90

3. Electric switch operating mechanism including a coil box having an open end, a support to which said box is secured, said support forming a closure for said open end, said box having an aperture through a side wall, a removable cover for said aperture, and a coil in said box adapted to be removed therefrom through said aperture. 95

4. Electric switch operating mechanism including a box adapted to hold a switch tripping coil, said box having an opening in the bottom wall thereof through which the coil is adapted to be passed, a tripping coil contained loosely in said box, a tube containing a movable core passed through said coil and aligned apertures in the top and bottom walls of said box, and adapted to hold said coil in place, and means to secure said tube removably to said coil box. 105

5. Electric switch operating mechanism including a coil box having an aperture in 110 its bottom wall through which a coil is adapted to be passed, a tripping coil contained loosely in said box, and externally-extended means arranged to secure said coil removably in place in said coil box. 120

6. Electric switch operating mechanism including a coil box having an aperture in its bottom wall through which a tripping coil is adapted to be passed, a plate secured removably to said coil box to close said aperture, said plate having an aperture therethrough and the top wall of said coil box having an aperture aligned with said plate-aperture, a tripping coil disposed loosely in said box, a tube containing a movable core 125 130

- extended loosely through said aligned apertures and said coil, whereby to hold said coil in place and means to secure said tube movably in position in said coil box.
5. Electric switch operating mechanism including a support, a coil box secured to said support, a tripping coil contained therein, a switch-locking device disposed above said box in operative relation with said tripping coil, and means to remove said coil from said box without removing said box from said support.
- 10

8. Electric switch operating mechanism including a coil box having an opening, a closure for said opening, a tripping coil contained loosely within said box, and a tube containing a movable core passed loosely through aligned openings in the opposite walls of said coil box and said coil and secured removably to said coil box, whereby to hold said coil removably in place. 15

In testimony whereof, I have signed my name to this specification.

CHESTER D. AINSWORTH.
